UNITED STATES PATENT OFFICE

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

THREAD CLEARER FOR LOOMS

Application filed November 22, 1928. Serial No. 321,203.

This invention relates to improvements in thread clearers for looms and it is the general object of the invention to provide a yieldable device of this type which will prevent breakage.

In the type of clearer to which my invention relates there is a notched bar located under the lay and positioned to engage the trailing weft end from the ejected bobbin. The notched bar extends behind the downward path of the ejected bobbin when the lay is on front center. The picker stick on certain types of looms where a clearer is desirable moves substantially along the longitudinal axis of the shuttle, so that should the picker stick fail to assume its proper upward position upon a forward beat of the loom it will strike the clearer and cause breakage.

As a result of continued transfers there accumulates on the bar a mass of weft ends which must be withdrawn from time to time. With the loom running and the bar in its normal position an element of risk is involved in removing these waste ends unless the bar can be moved to a position of safety. It is accordingly a further object of my present invention to provide the bar with a yielding support which will permit the same to be moved forwardly out of the path of the lay and picker stick to permit clearing of the waste ends while the loom is in operation.

It also happens that occasionally a bobbin will be so disposed during a forward stroke of the lay as to engage the thread clearer and unless the latter is yieldable breakage either of the clearer or bobbin will result.

A more detailed object of my invention relates to the manner of mounting the clearer. Multicolor magazines or weft replenishing mechanisms are customarily made with a pair of substantially parallel plates between which the bobbins lie. These plates are held together by tie rods and it is a more particular object of my present invention to employ one of these tie rods as a means for supporting the thread clearer to the end that the clearer and magazine may be assembled as a unit.

With these and other objects in view which will appear as the description proceeds, my

invention resides in the combination and arrangement of parts hereinafter described and set forth in the claims.

In the accompanying drawings wherein a convenient embodiment of my invention is set forth,

Fig. 1 is an end elevation of a weft replenishing mechanism having my invention applied thereto,

Fig. 2 is a top plan view looking downwardly in the direction of arrows 2 in Fig. 1, and

Fig. 3 is a detailed vertical section on line 3—3 of Fig. 1.

Referring particularly to Figs. 1 and 2, I have shown a loomside 10 on which is supported the foot 11 of a magazine M. The latter includes in its construction a plurality of tie rods one of which is illustrated at 12 as projecting beyond the magazine M. Said tie rod extends between the outer plate 13 and the inner plate 14 and may be held in position by screws one of which is shown at 15. Bobbins not shown move downwardly in the magazine and are moved toward transfer position by mechanism not set forth herein but well understood.

The lay L is mounted on swords one of which is shown at 16 and is provided with a longitudinally extended slots 17 through which an exhausted bobbin may be ejected from the shuttle S. A bobbin chute 18 is secured to the lay and has a forwardly and downwardly inclined surface 19 serving to deflect the ejected bobbin forwardly into a bobbin can not shown. As set forth herein the upper end of the inclined surface 19 terminates an appreciable distance below the under face of the lay.

The matter thus far described is of common construction, forming no part of my present invention, and may be made as set forth in prior patent to Ryon No. 1,030,748.

My invention relates particularly to the thread clearer and in carrying my invention into effect I provide a holder 30 which is held to the aforesaid tie rod 12 by means of a screw 31 as shown in Figs. 1 and 3. Said holder has a depending extension 32 into which is extended a rod 33. The latter rod

is held in adjusted longitudinal position in the extension 32 by means of a screw 34.

Secured to the lower end of the rod 18 is a coil spring 35 the upper end of which 5 fits tightly over and is held by frictional contact with the aforesaid rod. An upward extension 36 of a weft end clearing element 37 also fits closely in the spring and is held by the latter in a normally fixed position. A 10 notched horizontal arm 38 forms part of the clearing element and is proportioned to extend under the lay and into the space between the latter and the upper end of the surface 19.

The arm 38 is similar in purpose and general construction to the notched bar shown in Marcoux Patent No. 766,151 and when the lay is in the forward position shown in Fig. 1 the arm lies behind the slot 17 so that an ejected bobbin will pass in front of said 20 notched bar.

In operation at the time of transfer the ejected bobbin will move downwardly so that the trailing end, which extends through the eye of the shuttle will lie in front of the 25 arm 38. As the lay recedes one or another of the notches in the arm 38 will engage the weft end W of the expelled bobbin E and withdraw the same from the shuttle. This 30 operation of the device is substantially the same as in the aforesaid Marcoux patent.

The spring 35 is sufficiently strong to hold the bar 38 in proper position for all normal operations of the loom, adjustment of the arm in a vertical direction being accomplished by adjusting the rod 33 in the extension 32 and adjustment of the said arm in a horizontal direction being accomplished by moving the holder 30 angularly with respect to the tie rod 12.

40 Should the picker stick indicated at P in Fig. 1 be improperly placed on a forward beat of the lay so as to engage the arm 30 the latter will move forwardly due to the resilience of the spring 35. It will be observed that the said arm 38 need not necessarily move about the tie rod as a pivot inasmuch as the spring 35 will permit the arm 38 to move in any direction from its normal position. This is due partly to the fact that 45 the thread clearer 37 has a rearwardly extending arm 40. In like manner if the attendant desires to clear an accumulation of waste from the arm 38 he may do so by pulling said end forwardly and holding the portion 40 with one hand while removing the objectionable waste with the other hand, this 55 operation taking place while the loom is in operation and being accomplished of course by a deflection of the spring 35.

60 From the foregoing, it will be seen that I have provided a simple resilient mounting for a weft end clearer which will permit the latter to move forwardly when engaged by a misplaced picker stick or bobbin. It will 65 also be seen that said clearer may be moved

forwardly at will for the purposes of removing waste while the loom is in operation, the spring acting to return the clearer to normal position. It will also be seen that the device is mounted on one of the tie rods of the magazine and for this reason can be made as a part of the magazine. It will further be seen that the adjustments previously described permit the location of the notched arm 38 in the correct position with respect to the lay and the bobbin chute.

Having thus described my invention it will be seen that changes and modifications may be made therein by those skilled in the art without departing from the spirit and scope of the invention and I do not wish to be limited to the details herein disclosed, but what I claim is:

1. In a thread clearer for a loom having a lay with a slot therein for the passage of an ejected bobbin, a fixed support, a notched bar to lie under and behind the slot in the lay when the latter is in its forward transferring position, and a yielding connection between the support and the notched bar whereby the latter may move forwardly from its normal position, said connection constituting the sole means of support for the notched bar and holding the latter in normal position.

2. In a thread clearer for a loom having a lay with a slot therein for the passage of an ejected bobbin, a fixed support, a notched bar to lie under and behind the slot in the lay when the latter is in its foremost position, and a coil spring operatively connected to the notched bar, said support and notched bar being connected together by means of the spring only.

3. In a thread clearer for a loom having a lay with a slot therein for the passage of an ejected bobbin, a fixed support comprising a cylindrical member, a notched bar to lie under and behind the slot in the lay when the latter is in forward position, a cylindrical element operatively connected to the notched bar, and a coil spring fitted over and frictionally engaging the cylindrical member and the cylindrical element and holding the notched bar yieldingly in normal position.

4. In a thread clearer for a loom having a lay with a slot therein for the passage of an ejected bobbin, a fixed support, a notched bar to be located behind and below the slot in the lay when the latter is in forward position, a forward extension of the bar, and a coil spring operatively connecting the fixed support and forward extension and being the only means of support for the notched bar and holding the latter yieldingly in normal position.

5. In a thread clearer for a loom having a lay with a slot therein in which a picker stick moves, a notched bar located behind and below the slot when the lay is in forward position, a fixed support, and a yielding connec-

tion between the fixed support and the notched bar comprising a coil spring which is the sole connection between the fixed support and the notched bar.

5. In a loom having a lay with a bobbin slot therein, a weft replenishing magazine, a tie rod forming part of the magazine, a normally fixed support angularly and longitudinally adjustable on the tie rod, a notched bar to extend behind and below the slot in the lay when the latter is in forward position, and a yielding connection between the notched bar and the support on the tie rod, said connection constituting the sole means of support for
10 the notched bar and holding the latter in normal position.

6. In a weft replenishing mechanism for a loom having a lay provided with a slot therein through which an ejected bobbin may pass, a tie rod forming part of the replenishing mechanism, a holder extending downwardly from and angularly adjustable with respect to the tie rod, a coil spring supported by the holder, and a notched rod located behind and
25 below the slot in the lay when the latter is in forward position, said spring comprising the sole connection between the holder and the notched bar and yielding to permit the latter to move forwardly.

7. In a weft replenishing mechanism having a lay provided with a slot for an ejected bobbin, a tie rod forming part of the replenishing mechanism, a depending carrier supported by and angularly adjustable with respect to the carrier, a vertical coil spring having the upper end frictionally held on the holder by the resilience of said spring, and a notched bar located behind and below the slot in the lay when the latter is in forward position, the lower end of said spring being operatively connected to the notched bar.
30

8. In a weft replenishing mechanism having a lay provided with a slot for an ejected bobbin, a tie rod forming part of the replenishing mechanism, a depending carrier supported by and angularly adjustable with respect to the carrier, a vertical coil spring having the upper end frictionally held on the holder by the resilience of said spring, and a notched bar located behind and below the slot in the lay when the latter is in forward position, the lower end of said spring being operatively connected to the notched bar by having friction contact with said notched bar
45 due to the resilience of the spring.
50

In testimony whereof I have hereunto affixed my signature.

RICHARD G. TURNER.
